ULTRA HIGH FREQUENCY AMPLIFIER

Lester J. Wolf, Audubon, N. J., assignor to Radio Corporation of America, a corporation of Delaware

Application July 28, 1939, Serial No. 286,977

5 Claims. (Cl. 179—171)

This invention relates to radio frequency amplifiers, and particularly to an ultra high frequency amplifier circuit suitable for use in a television transmitter.

One of the objects of the present invention is to provide a coupling circuit between the output of one amplifier and the input of a succeeding amplifier which will minimize the effect of wide impedance variations of the said input upon the output of the preceding stage.

Another object is to provide an efficient radio frequency amplifier circuit consisting of a pair of cascaded push-pull stages coupled together by a circuit insuring a desired amount of radio frequency drive impressed upon the last of said stages, and satisfactory grid regulation therefor.

A feature of the present invention involves the use of a coupling circuit between the output of one radio frequency amplifier stage and the input of a succeeding radio frequency amplifier stage, employing a pair of nichrome resistors in the form of a loop for inductively coupling said stages together.

A more detailed description of the invention follows, in conjunction with a drawing whose single figure shows, schematically, an amplifier circuit embodying the principles of the invention.

In the drawing, an amplifier stage comprising vacuum tubes 13 and 14 connected in push-pull relation is arranged to drive a second amplifier stage 1, 2, also in push-pull relation. Both of these stages are provided with cross-neutralization schemes for eliminating capacity coupling between the associated input and output circuits, so as to stabilize the amplifier and prevent self-oscillation. The tuned input circuit 26 of the first stage 13, 14 is coupled to a preceding oscillator, or other suitable source of high frequency energy, not shown, while the output circuit 21, 22 of the second stage 1, 2 is coupled to a transmission line extending to an antenna. The input circuit of stage 13, 14 is provided with resistors 20, 20 which enable the adjustment of individual bias for the grids of tubes 13 and 14 and permit the use of individual meters for reading the D. C. grid current.

The tuned output circuit for amplifier stage 1, 2 comprises an inductance 21 shunted by a variable condenser 22. Inductance 21 is in the form of a parallel conductor loop which is electrically one-quarter wavelength long from the center of the shorting bar to the anodes of the tubes 1 and 2. Coupled to the inductance 21 is a coil 24 in series with a condenser 25, both connected in turn to a coaxial cable 23 extending to an an-

tenna system, not shown. Condenser 25 serves to tune out the reactance of coil 24.

The active parts of the filaments of vacuum tubes 1 and 2 are maintained at ground or zero radio frequency potential by means of connections which are one-half wavelength long and tuned or maintained at this length by slider 36. The mid point of the filament of each tube is thus effectively grounded for radio frequency potentials and the filament leads including the lengths within the vacuum tubes are tuned out.

The cross-neutralization scheme used in push-pull amplifier stage 1, 2 departs somewhat from the conventional neutralizing circuit shown used in connection with amplifier stage 13, 14, in that capacitors are provided for compensating for the reactance of the leads in the neutralizing circuit. The main neutralizing capacitors are made by semi-cylindrical outer armatures or plates 3 and 4 placed around the anode jackets of tubes 1 and 2, respectively. The neutralizing capacitor formed by plate 3 and the anode jacket of tube 1 has a value equal to the grid-anode capacity of tube 2. Similarly, the neutralizing capacitor formed by plate 4 and the anode jacket of tube 2 has a value equal to the grid-anode capacity of tube 1. Capacitor 5 compensates for the reactance of the lead extending from semi-cylindrical plate 3 to a distance substantially half way between capacitors 5 and 6. Similarly, capacitor 9 compensates for the reactance of the lead extending from semi-cylindrical plate 4 to a distance half way between capacitors 9 and 7. In the same way, capacitor 7 in series with the grid of vacuum tube 1 compensates for the reactance of the lead extending from the grid of vacuum tube 1 to a distance half way between capacitors 7 and 9. Also, capacitor 6 in series with the grid of vacuum tube 2 compensates for the reactance of the lead extending from the grid of vacuum tube 2 to a distance half way between capacitors 6 and 5.

The driving stage 13, 14 is not provided with compensating capacitors 5, 6, 7 and 9, because the leads going to the neutralizing elements of tubes 13 and 14 do not have the reactances that exist in the leads in circuit with tubes 1 and 2. In practice, vacuum tubes 13 and 14 are small, perhaps seven or eight inches over-all length, whereas the length of vacuum tubes 1 and 2 is perhaps some four feet, more or less.

The output circuit for the first stage comprises a parallel conductor loop 15 having a variable trimmer condenser 17 in shunt therewith for tuning the loop. This loop 15, which develops a

high circulating current for radio frequency, is electrically one-quarter of a wavelength long, as measured from each anode of tubes 13, 14 to the midpoint of the shorting bar across the legs of the loop 15. The resistor 19 in the output circuit serves to reduce parasitic currents.

For coupling the output circuit 15 to the grids of the succeeding amplifier stage 1, 2, there is provided a coupling circuit 11 which can be considered as consisting of two parts separated by condensers 16, 16; first, a loop 11' to the right of the condensers 16, 16 which is electrically one-quarter wavelength long and is inductively coupled to the output loop 15, and secondly, a section to the left of condensers 16, 16 which is electrically one-half wavelength long.

The electrical half wavelength section between condensers 16, 16 and the grids of tubes 1, 2 includes a pair of nichrome resistors 8 and 10 which are characterized by an extremely high resistance-to-inductance ratio and are non-reactively wound to further diminish the reactive component. The resistors 8 and 10 serve the purpose of minimizing the effects of wide impedance variations of the grids of tubes 1 and 2 upon the transmission line 11. In practice, the modulation impressed upon the grids of tubes 1 and 2 is effected by varying the bias voltage on these tubes, but the ratio between the peak-to-peak swing of that bias voltage and the peak value of the radio frequency voltage must be essentially unity. In the presence of the wide variations in impedance of the grids of tubes 1 and 2, and in the absence of the nichrome, the value of the radio frequency voltage would vary over limits which would not produce satisfactory modulation characteristics. Introduction of the nichrome spirals 8 and 10 reduces the impedance variations by coupling circuit or transmission line 11 to the point where the circuit is then practical. Ordinarily, the impedance variations across the grids of vacuum tubes 1 and 2 vary from perhaps 100 ohms up to several thousand ohms. The insertion of the nichrome resistors 8, 9 in the manner shown in the drawing prevents these large variations in impedance from being impressed upon the transmission line so that in practice the output of the vacuum tubes 13 and 14, in relation to the input of tubes 1 and 2, is substantially constant. Putting it another way, we can say the nichrome resistors 8 and 10 stabilize the impedance of the output or driving amplifier stage 13, 14.

Air blowers 31, 31 serve to dissipate the heat developed in the nichrome resistors.

The loop 11' includes a pair of nichrome resistors 12, 12 which are disposed in loose inductive coupling relation to the shorting bar across loop 15. The junction point of the nichrome resistors 12, 12 is shown connected to the mid point of loop 15, although if desired this connection may be eliminated and the junction point grounded. The loop including resistors 12, 12 diminishes the voltage appearing at the condensers 16, 16 and therefore diminishes the voltage appearing at the grids of tubes 1 and 2, while at the same time the nichrome resistors restrict the impedance variations in the transmission line 11 and provide improved control of tubes 13 and 14. Due to the resonant rise in current in the quarter wavelength loop 11', by virtue of its length, there is developed a high potential between capacitors 16, 16 on the condenser plates nearest the nichrome resistors 12, 12, at which location the impedance of the circuit is very high. The condensers 16

are placed at a high radio frequency voltage, and a low radio frequency current value because it is necessary to minimize the shunting effect of the pickup circuit capacity-to-ground so as to minimize the load on the modulator. On the other hand, it is necessary to transmit a considerable amount of radio frequency power through these condensers. Consequently these condensers are located in the circuit where the radio frequency voltage is very high and the radio frequency current is very low. Therefore, condensers having a very low capacity may be used without appreciable radio frequency voltage drop.

It should be noted that capacitors 7 and 6 serve to block the passage of direct current through the electrical half wavelength section of the inter-stage coupling circuit. Modulating voltage is introduced at the grids of the modulating amplifier 1, 2 through chokes 18 connected to lead 28 which extends to a modulator device not shown.

What is claimed is:

1. In an amplifier system having first and second stages of discharge tubes arranged for push-pull operation, an output circuit for the first stage and an input circuit for the second stage, the electrical lengths of said output and input circuits being optimally determined in relation to the working wave lengths for which said system is adapted, and the ohmic resistance values of said circuits being large relative to their electrical lengths and being determined by the use of a high resistance metal in their conductors, means providing reactive coupling between said output and input circuits, means providing optimum values of inductance and capacitance in said circuits for transfer of ultra high frequency energy of said working wave lengths, and means including shield plates external to the tube envelopes of said second stage and formed closely about the same so as to be disposed in capacitively reactive relation to the electrodes within said tubes for neutralizing the inter-electrode capacitances of said second stage tubes.

2. An amplifier system for ultra high frequencies comprising an amplifier stage having a pair of vacuum tubes each including a grid, a cathode and an anode, an input circuit between said grids for applying ultra high frequency potentials thereto, a connection between said cathodes, and an output circuit comprising an electrically conducting loop of wire with a condenser in shunt to the legs of said loop coupled between said anodes, said loop having a length which is electrically one-quarter of a wavelength long at the operating frequency as measured from each anode to the electrical center of said loop, a succeeding amplifier stage also having a pair of vacuum tubes each including a grid, a coupling circuit between the grids of said last stage and said output circuit for applying potentials to said grids which are out-of-phase relative to each other, said coupling circuit having a pair of nichrome resistors connected together, each of which is inductively coupled to a portion of said output circuit, a condenser in each side of said coupling circuit, the distance between each condenser and the junction point of said resistors being electrically one-quarter of a wavelength at the operating frequency, said coupling circuit being electrically three-quarters of a wavelength long at the operating frequency as measured from each grid of the last stage to the junction point of said nichrome resistors.

3. An amplifier system in accordance with claim 2, including a non-inductively wound

nichrome resistor located in said coupling circuit between each condenser and a grid of one tube of said succeeding amplifier stage.

4. An amplifier system for ultra high frequencies comprising an amplifier stage having a pair of vacuum tubes each including a grid, a cathode and an anode, an input circuit between said grids for applying ultra high frequency potentials thereto, a connection between said cathodes, and an output circuit comprising an electrically conducting loop of wire with a condenser in shunt to the legs of said loop coupled between said anodes, said loop having a length which is electrically one-quarter of a wavelength long at the operating frequency as measured from each anode to the electrical center of said loop, a succeeding amplifier stage also having a pair of vacuum tubes each including a grid, a coupling circuit between the grids of said last stage and said output circuit for applying potentials to said grids which are out-of-phase relative to each other, said coupling circuit having a pair of nichrome resistors connected together, each of which is inductively coupled to a portion of said output circuit, a condenser in each side of said coupling circuit, the distance between each condenser and the junction point of said resistors being electrically one-quarter of a wavelength at the operating frequency, said coupling circuit

5 being electrically three-quarters of a wavelength long at the operating frequency as measured from each grid of the last stage to the junction point of said nichrome resistors, a nichrome resistor wound to reduce the reactive component located between each condenser and a grid of one of said tubes of said last amplifier stage, choke coil means connected across the grids of said last stage, and a connection to the center of said choke coil means for applying modulating potentials to the grids of said last stage.

10 5. A coupling circuit between a source of high frequency energy and a balanced circuit, comprising an electrically conducting loop having a pair of nichrome resistors directly connected together, each of which is inductively coupled to said source of high frequency energy, a condenser in each leg of said loop located between said resistors and said balanced circuit, said loop having a length which is electrically three-quarters of a wavelength long as measured from said balanced circuit to the junction point of said resistors, the distance between said condensers and said junction point being electrically one-quarter of a wavelength at the operating frequency, and cooling means of the air-blast type for dissipating heat which certain of said resistors radiate.
